CLAIM

The ornamental design for a bluetooth FM transmitter, as shown.

DESCRIPTION

FIG. 1 is a front elevational view of a bluetooth FM transmitter showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a front perspective view thereof.

The claimed bluetooth FM transmitter is used to transmit audio from a bluetooth enabled device to FM radio.
